Item A Fibro Source, U.S.A. Inc. Sharpener Jun. 14, 2010.

Primary Examiner — Derrick Holland*Assistant Examiner* — Andrew Kerr(74) *Attorney, Agent, or Firm* — John F. A. Earley, III; Frank J. Bonini, Jr.; Harding, Earley, Folmer & Frailey, PC**CLAIM**

The ornamental design for a sharpener, as shown and described.

DESCRIPTION

FIG. 1 is a perspective view of a first embodiment of a sharpener according to my new design;

FIG. 2 is a front elevation view, the rear elevation view being a mirror image thereof;

FIG. 3 is a right side elevation view, the left side elevation view being a mirror image thereof;

FIG. 4 is a top plan view thereof; and

FIG. 5 is a bottom plan view thereof;

FIG. 6 is a perspective view of a second embodiment of a sharpener according to my new design;

FIG. 7 is a front elevation view, the rear elevation view being a mirror image thereof;

FIG. 8 is a right side elevation view, the left side elevation view being a mirror image thereof;

FIG. 9 is a top plan view thereof; and,

FIG. 10 is a bottom plan view thereof.

The broken lines shown in the figure drawings that abut the full line and shaded surfaces represent the boundary therein and form no part of the claimed design.

The broken lines shown in the figure drawings are for the purpose of illustrating environmental structure and form no part of the claimed design.
